UNITED STATES PATENT OFFICE.

WILLIAM ANCIL LORIMER, OF ZANESVILLE, OHIO.

METAL CAP FOR CONICAL TENTS.

1,198,935.

Specification of Letters Patent. Patented Sept. 19, 1916.

Application filed March 30, 1916. Serial No. 87,767.

To all whom it may concern:

Be it known that I, WILLIAM ANCIL LORIMER, a citizen of the United States, residing at Zanesville, in the county of Muskingum and State of Ohio, have invented certain new and useful Improvements in Metal Caps for Conical Tents; and I do hereby declare the following to be a full, clear, and exact description of the invention, such as will enable others skilled in the art to which it appertains to make and use the same.

My invention relates to improvements in conical wall tents adapted for use in the field, and more especially adapted for military purposes, and it consists in providing a telescopic metal cap adapted to form a closed top for said tent, and at the same time to permit the passage therethrough of a pipe from a stove contained in said tent and used for heating or cooking purposes.

My invention will be understood by reference to the accompanying drawings, in which the same parts are indicated by the same reference symbols throughout the several views.

Figure 1 is a perspective view showing a tent complete, with the metal cap thereon, parts being broken away; and Figs. 2 and 3 are details showing in perspective the two members of the telescopic metal cap.

A represents the body portion of the tent which is constructed and secured to the ground in the usual way. The top of this body portion A terminates in a ring a, to which is attached a chain bridle B, connected to a smaller ring C which is adapted to slip over the tip d of the tent pole D.

The metal cap is composed of a series of telescopic members, each in the form of a frustum of a hollow cone. In the drawings I have shown two such members E and E', each provided with suitable beads e, the inner and upper member being provided with a closed cap e' perforated, as at e², to receive the tip d of the tent pole D, and is also preferably provided with brackets e³ to engage the ends of the handle e⁴, by means of which either the member E' or the two members E' and E, when in the telescoped position, may be conveniently transported.

The two members E and E' of the metal cap are each provided with a suitable elliptical slot e⁰ which, when the parts are in the position shown in Fig. 1, form an opening to permit the passage therethrough of

the smoke pipe F from the stove G, shown in dotted lines in Fig. 1.

It will be seen that when the parts are in the position shown in Fig. 1, with the stove pipe in place, that the said stove pipe will serve as a lock to prevent the members E or E' from sliding relative to each other, or from turning laterally. When the stove is not used in the tent, the slots e⁰ are closed by a cover E², hinged as at e⁵ to one of the members of the metal cap. In warm weather the slots e⁰ may be used as a means for letting hot air out of the top of the tent, thus assisting in ventilating the tent, and the cover E² may be swung to the closed position when desired, as in case of rain. The metal cap is preferably provided with suitable stays H.

While I have shown the metal cap made of two telescopic sections, it will be evident that it may be made of a series of shorter telescopic sections, each in the form of a frustum of a hollow cone, and the upper and inner section is closed at the top by means of a suitable diaphragm, such as is shown at e' in Fig. 2. By having the cap made of a plurality of sections, collapsible as shown, it is especially adaptable to various sizes of tents, especially the smaller sizes, and may be stored in a convenient, compact form when the tent is being transported from place to place. When the tent is struck, the metal cap is preferably rolled up with the body of the tent and with such other articles, such as blankets, beddings, etc., as are usually rolled up therein, but if desired it may be transported separately.

It will be obvious that various modifications might be made in the herein described apparatus, and in the construction, combination and arrangement of parts which could be used without departing from the spirit of my invention.

Having thus described my invention what I claim and desire to secure by Letters Patent of the United States is:

1. A metal cap for conical wall tents, comprising a plurality of telescoping metal members each in the form of a hollow frustum of a cone, a plate closing the upper end of the inner member, and means for attaching said plate to the tent pole, substantially as described.

2. A metal cap for conical wall tents, comprising a plurality of telescoping metal

members each in the form of a hollow frustum of a cone, a plate closing the upper end of the inner member, and means for attaching said plate to the tent pole, said cap being provided with an opening at its side to receive the smoke pipe of a stove mounted in said tent, substantially as described.

3. A metal cap for conical wall tents, comprising a plurality of telescoping metal members each in the form of a hollow frustum of a cone, a plate closing the upper end of the inner member, and means for attaching said plate to the tent pole, said cap being provided with an opening at its side to receive the smoke pipe of a stove mounted in said tent, with a cover hinged to one of said members and adapted to close said opening when desired, substantially as described.

4. A metal cap for conical wall tents comprising a pair of telescoping metal members each in the form of a hollow frustum of a cone, a plate closing the upper end of the inner member, and means for attaching said plate to the tent pole, substantially as described.

5. A metal cap for conical wall tents comprising a pair of telescoping members each in the form of a hollow frustum of a cone, a plate closing the upper end of the inner member, and means for attaching said plate to the tent pole, said cap being provided with an opening at its side cut partly in each of said members at the junction thereof, to receive the smoke pipe of a stove mounted in said tent, substantially as described.

6. A metal cap for conical wall tents comprising a pair of telescoping members each

in the form of a hollow frustum of a cone, a plate closing the upper end of the inner member, and means for attaching said plate to the tent pole, said cap being provided with an opening at its side cut partly in each of said members at the junction thereof, to receive the smoke pipe of a stove mounted in said tent, with a cover hinged to one of said members and adapted to close said opening when desired, substantially as described.

7. In a conical wall tent, the combination with a body portion provided with a ring at its upper end, and a bridle connected to said ring, of a tent pole supporting said bridle, and a metal cap formed of a plurality of telescopic metal members, each in the form of a frustum of a cone, the lower member being adapted to fit snugly against said ring, and the upper member being closed by a perforated plate adapted to engage the head of the tent pole, substantially as described.

8. In a conical wall tent, the combination with a body portion provided with a ring at its upper end, and a bridle connected to said ring, of a tent pole supporting said bridle, and a metal cap formed of a plurality of telescopic metal members, each in the form of a frustum of a cone, the lower member being adapted to fit snugly against said ring, and the upper member being closed by a perforated plate adapted to engage the head of the tent pole, with stays for said cap, substantially as described.

In testimony whereof, I affix my signature.

WILLIAM ANCIL LORIMER.
